UNITED STATES PATENT OFFICE

STEPHEN SHUKO, OF BOSTON, MASSACHUSETTS

FLORAL-PILLOW SUPPORT

Application filed February 11, 1929. Serial No. 339,132.

This invention relates to a floral pillow support, the general object of the invention being to provide a foldable support which, when set up, will support a floral pillow which may be formed on the support or suitably attached thereto and with means whereby the support can be folded so that it will occupy but little space when in use and can be easily handled.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is a perspective view of the device in operative position.

Figure 2 is a side view of Figure 1.

Figure 3 is a fragmentary view with parts broken away, showing how the forwardly extending brace member engages the front supporting yoke.

Figure 4 is a view showing the device in folded position.

Figure 5 is a section on line 5—5 of Figure 4.

Figure 6 is a detail view with parts broken away, showing how the rearwardly extending brace member engages the rear yoke when the parts are in the position shown in Figures 4 and 5.

Figure 7 is a rear view showing the device in a folded position, with the rear yoke folded upon the frame.

Figure 8 is a perspective view showing how the rear brace engages the rear yoke when the parts are in unfolded position.

Figure 9 is a similar view showing how the rear yoke is moved between the limbs of the rearwardly extending brace when the parts are to be folded into the position shown in Figure 7.

In these views, the numeral 1 indicates a substantially rectangular frame formed of wire or the like with its side and end pieces bent inwardly into arc shape. A wire 2 ex-

tends through the center of the frame with its ends wrapped around the end pieces of the frame and a rod or wire 3 is placed at right-angles to the frame 2 and has its ends bent around the side pieces of the frame. Other wires or rods 4 extend from one end piece to the other of the frame on each side of the member 2, with their ends bent around the end pieces of the frame, and these wires are attached to the member 3 by the wire 5, as clearly shown in Figure 1. A front yoke member 6 has the extremities of its limbs bent around the bottom side piece of the frame, the bight of the member forming an engaging element for a surface upon which the device is placed. A rear yoke 7 has the extremities of its limbs bent around the upper or rear cross piece of the frame with its bight adapted to engage the surface upon which the device is placed so that the two yokes act as legs for the frame. Each yoke member has each limb thereof bent inwardly and outwardly adjacent its junction with the bight so as to form the loop 8 and the keeper recess 9.

A rearwardly extending brace member 10 of yoke shape has the extremities of its limbs bent around the front or lower side piece of the frame and a forwardly extending brace member 11, also of yoke shape, has the extremities of its limbs bent around the upper or rear side piece of the frame. Each of these brace members is formed with the loops 12 at the junction of its limbs with its bight, these loops slidingly engaging the front and rear members 6 and 7 and when these loop portions engage the keeper recesses 9, the parts are held in a position with the front and rear yoke in a vertical position so that the frame is supported in an inclined position as the front yoke is much shorter than the rear yoke. This position is shown in Figures 1 and 2. Thus a floral pillow or other floral design can be readily placed on the inclined frame, the design being suitably connected with the frame or it may be formed by placing the flowers in the spaces formed by the frame and the wires thereof.

When the device is not in use, the forwardly and rearwardly extending brace members

have their loop portions forced out of the keeper recesses and the parts are then moved to the position shown in Figures 4 and 5 so that the device will be flat, with the front yoke extending forwardly of the frame and the rear yoke extending rearwardly of the frame. In this position, the device will occupy but little space and can be readily handled.

If desired, the limbs of the rear yoke are pressed toward each other so that they will pass between the limbs of the rearwardly extending brace, as shown in Figure 9, so that the rear yoke can be folded against the rear part of the frame, with the front yoke extending forwardly, as before. This position of the parts is shown in Figure 7, and as will be seen, when the device is folded, as shown in Figure 7, it will occupy less space than when the device is folded, as shown in Figures 4 and 5.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

1. A device of the class described comprising a frame, a yoke member having its limbs pivotally connected with the front of the frame, a rear yoke member having the ends of its limbs pivotally connected with the rear of the frame, a rearwardly extending brace member of yoke shape having its limbs pivotally connected with the front of the frame, a forwardly extending brace member of yoke shape having the ends of its limbs pivotally connected with the rear of the frame, portions of the brace members slidably engaging the limbs of the front and rear yoke members, the front yoke member being shorter than the rear member and means for locking the brace members to the outer portions of the front and rear yoke members to hold said front and rear members in vertical position whereby said members will support the frame in inclined position.

2. A device of the class described comprising a frame, wires arranged in the frame whereby flowers or the like can be arranged in the frame, front and rear yoke-shaped supporting members pivotally connected with the front and rear portions of the frame, with the bight portions outermost, each limb of each yoke-shaped member having a keeper recess therein adjacent the bight portion, a rearwardly extending brace member of yoke shape having its limbs pivotally connected with the front of the frame with loops formed at the ends of its bight portion for slidably engaging the limbs of the rear yoke, a forwardly extending brace member of yoke shape hav-

ing the ends of its limbs pivotally connected with the rear part of the frame with loops at the ends of its bight portion for slidably engaging the limbs of the front yoke, said loops, when engaged with the keeper recesses, frictionally holding the front and rear yoke members in vertical position whereby the frame is supported by said yoke-shaped members, with the front yoke of less length than the rear yoke to hold the frame in inclined position when the parts are in operative position.

In testimony whereof I affix my signature.
STEPHEN SHUKO.
